PATCH POCKET

William M. Masi, Los Angeles, Calif.

Application March 17, 1952, Serial No. 276,917

1 Claim. (Cl. 2—247)

1

This invention relates to improvements in pockets, particularly to that type of pocket generally referred to as a patch pocket.

An object of the invention is to provide an improved patch pocket and method of making the same which is so designed that all of the stitching therein may be performed by machine and the pocket is adequately reinforced at localities requiring strength.

More specifically, an object of the invention is to provide a pocket and method of making the same so designed that the outer material of the pocket may be caused to line up or register with the design of the material forming the body of the garment.

Explanatory of the present invention it has heretofore been quite difficult to make and locate patch pockets of plaid material and have the plaid design on the outer pocket material line up or register with the plaid design on the body of the garment. This has been largely occasioned by the practice of largely sewing the lining for the patch pocket to the outer material thereof prior to its application to the body of the garment. In sewing the lining material to the outer pocket material the outer pocket material is usually stretched or distorted in the course of the sewing operation so that when the outer pocket material and lining material have been joined around their side edges and bottom edges the outer pocket material acquires a permanently distorted shape. Consequently when it is applied to the material of the garment it is very difficult to overcome this distortion with the result that the plaid design on the outer pocket material cannot be caused to perfectly register with the plaid design on the garment material. The present invention enables a saving of the cost of operation of the hand work and enables the obtaining of pockets of uniform quality and greater strength.

In accordance with the improved method, the lining material is secured to the outer pocket material only across its top edge and thereafter the side edges of the outer pocket material are suitably prepared. The outer pocket material may then be positioned on the garment material so that the design thereon can be caused to perfectly register with the design of the garment material. The lining can then be used to hold the outer pocket material in the position selected and secured to the garment material. Finally when the outer pocket material is caused to assume a position overlying the lining it may be secured to the garment while being held in prop-

2

er position by the already secured lining. In this way distortion of the outer pocket material can be avoided and a registration of the design on the patch pocket with the garment material is easily accomplished.

Still another object of the invention is to provide a patch pocket wherein the interior thereof is completely finished, that is, there are no in-turned raw edges of material exposed on the interior of the pocket.

With the foregoing and other objects in view, which will be made manifest in the following detailed description and specifically pointed out in the appended claim, reference is had to the accompanying drawings for an illustrative embodiment of the invention, wherein:

Fig. 1 is a view in plan showing the inner face of the outer section of pocket material and illustrating a preliminary step in the formation of the pocket;

Fig. 2 is a view in plan illustrating the outer face of the outer section of pocket material and illustrating a preliminary step, Fig. 2 being in the main a view of the reverse side of the material shown in Fig. 1;

Fig. 3 is a view similar to Fig. 2 but illustrating the attachment of the lining material thereto;

Fig. 4 is a view on the reverse side from Fig. 3 illustrating the manner in which the side and bottom edges of the outer pocket material can be largely finished;

Fig. 5 is a view similar to Fig. 4 but illustrating the manner in which the top is largely finished;

Fig. 6 is a view illustrating the manner in which the pocket can be centered with relation to the design on the garment;

Fig. 7 is a view similar to Fig. 6 but illustrating the manner in which the lining material is secured to the body of the garment; and

Fig. 8 is a similar view illustrating the pocket as being completed on the garment.

Referring to the accompanying drawings wherein similar reference characters designate similar parts throughout, 10 indicates a section of outer pocket material which is usually a portion of the same fabric as that from which the body of the garment is made so that the design of the material of the patch pocket will conform to the material of the body of the garment. This section is of approximately the same size and shape as the size and shape of the finished pocket but is a little larger to provide for certain in-turned edges, seams and stitching. The upper corners of the section 10 are preferably notched

out as at 11 and 12 and small indentations 13 and 14 may be formed in the side edges adjacent the top edge. On the reverse or inside face of the section 10 an edging tape 15, preferably straight tape, is secured such as by stitching 16. This edging tape extends from side edge to side edge of the section 10 and the stitching 16 may be applied by merely sewing the bottom edge of the tape 15 to the material 10 on a sewing machine.

The section 10 is then turned over as depicted in Fig. 2 and edging tape 17 is applied around its side and bottom edges. This edging tape is preferably bias tape and the stitching 18 may be applied by merely sewing the outer edge of the tape 17 along the outer edge of the section 10 by means of a sewing machine. A section of lining material 19 is then applied over the outer face of the section 10 and is attached thereto along its top edge such as by stitching 20. This stitching likewise may be applied by a sewing machine.

The assembly thus completed is then turned over and caused to assume the position shown in Fig. 4. In this figure the inner face of the outer garment material or the same face shown in Fig. 1 is disposed uppermost. The edging tape 17 is drawn around the side and bottom edges of the outer pocket material 10 and basted thereto such as by basting stitches 21 thus forming an in-turned or inwardly folded edge around the sides and bottom of the section 10. The basting stitching 21 may also be applied by machine. The lining material 19 is drawn upwardly and over the top of the section 10 so that the section 10 will be folded at its top along a line horizontally connecting the indentations 13 and 14. It is basted in this position, as indicated by the basting stitches 22, which can also be applied by machine. The side and bottom edges of the lining material 19 are left unattached in Fig. 5. The assembly thus produced is then pressed and after the pressing operation is completed it is positioned on the material of the garment G. If the garment G is formed of a plaid material the section 10 is assumed to likewise have been formed of the same material and it is desirable that the plaid design of the pocket material register or be aligned exactly with the plaid design of the garment material. The section 10 is adjusted both vertically and horizontally to cause its design to be aligned with the garment material. This involves a shifting or adjustment of the lining material 19 in conformity therewith. When the section 10 has been properly aligned with respect to the garment G it is folded back to expose the lining 19. The lining 19 remains stationary and positioned flatly against the garment material G. Suitable marks, indicated at 23, are applied across the edge portions of the lining material and onto the garment material G so that the lining material can be re-positioned with respect to the garment material G while it is being sewed thereto. If the material does not have a pattern such as a plaid, but is comparatively plain, the marks may be applied to the pocket material 10 and extended across onto the garment material, such as are indicated at 23a, to facilitate the re-positioning of the pocket on the garment. The outer pocket material 10 is then folded about its top edge. That is, it is swung upwardly so as to completely expose the lining material as depicted in Fig. 7. The outer pocket material then should be pressed. The basting stitches 22 are then pulled out and the assembly is tacked to the garment material

5 G by sewing back and forth several times at 24 and then stitching the lining material adjacent its side and bottom edges to the garment material along the line of stitching 25. At the end of the line of stitching 25 a similar tacking takes place at 26. With the lining material 19 thus sewed to the garment G at a locality where, if the section 10 is returned to an overlying position, its design will register with the design of the garment. It is possible to fold the section 10 from the position shown in Fig. 7 into the position shown in Fig. 8. When it is returned to its overlying position it will be found that its design registers perfectly with the design of the garment material. The outer pocket material 10 is then basted with basting stitches which may be performed by machine in this position. Its side and bottom edges are then stitched to the garment by stitching 27 which is located outwardly of the stitching 25. Preferably the stitching 27 extends through the outer pocket material, its inturned side and bottom edge portions, the edge portions of the lining material outwardly of the stitching 25 and through the garment material G. When this stitching which may also be applied by a sewing machine is completed the basting stitches 21 are removed and also the basting stitches which were used to hold the pocket in place during the application of the stitches 27 are also removed. The pocket is then complete.

30 It will be observed from the above construction that the side and bottom edges of the outer pocket material 10 are folded inwardly and that the stitching 27 applied adjacent the fold serves to firmly anchor the outer pocket material to the garment. Furthermore, as the stitching 25 extends through the lining material inwardly of its side edges and its bottom edge and into the garment material the ends and bottom of the pocket have a finished appearance. In other words, there are no raw or inturned edges which are exposed within the pocket. The top of the outer pocket material 10 is reinforced on its inner face by the binding tape 15 which in the completed pocket is enclosed between the outer pocket material and the inturned top edge thereof.

35 From the above described construction it will be appreciated that an improved pocket construction has been designed which will present a neat and attractive exterior appearance and which presents a finished interior. The construction is such that all of the sewing operations may 40 be performed by machine. At the same time it is possible to delay the attachment of the side and bottom edges of the lining to the outer pocket material until the final operation so that the outer pocket material will not become distorted prior to its application to the garment. Consequently it is possible to locate or center the outer pocket material so that its design will be aligned with the design of the garment material and, having located or centered the outer pocket material with respect thereto, the lining is secured to the garment serving as a holder or a marker holding the position of the outer pocket material so that when it is returned to the position shown in Fig. 8, it will bear its proper relationship to the design of the material of the garment.

45 Various changes may be made in the details of the construction without departing from the spirit and scope of the invention as defined by 50 the appended claim.

I claim:

The method of making patch pockets which consists of applying to the inner face of a section of outer pocket material a binding tape, securing the binding tape to said section across the top edge by stitching, positioning binding tape against the outer face of said section of outer pocket material around the side and bottom edges thereof, stitching the binding tape and the outer side and bottom edges together, stitching a section of lining to the top edge of the outer pocket material and through the first-mentioned binding tape to overlie the outer side thereof, drawing the lining material across the top edge of the section of outer pocket material and folding the top edge of the outer pocket material downwardly, basting the folded top edge of the outer pocket material in its folded positions, drawing the second-mentioned binding tape around the side and bottom edges of the 20

inner face thereof, positioning the lining material on garment material so that the design on the outer pocket material will register therewith, stitching the lining material to the garment material around its side and bottom edges and stitching the side and bottom edges of the outer pocket material to the garment material through the second-mentioned binding tape and through the edges of the lining outwardly of the stitching securing the side and bottom edges of the lining to the garment, and removing the basting.
